(57) **CLAIM**

The ornamental design for an adaptor plate, as shown and described.

DESCRIPTION

FIG. 1 is a perspective view of my adaptor plate;
FIG. 2 is a perspective view in the opposite orientation from that shown in FIG. 1;

FIG. 3 is a top plan view of the adaptor plate;
FIG. 4 is a side elevational view of the adaptor plate;
FIG. 5 is a side elevational view 180° apart from the view shown in FIG. 4;

FIG. 6 is a bottom plan view of the adaptor plate;
FIG. 7 is a side elevational view of the adaptor plate; and,
FIG. 8 is a side elevational view of the adaptor plate 180° from the view shown in FIG. 7.
